(57) **CLAIM**

I claim the ornamental design for a plastic molded lattice, as shown and described.

DESCRIPTION

FIG. 1 is a fragmentary perspective view of the plastic molded lattice showing the side that is cut.

FIG. 2 is a fragmentary perspective view of the plastic molded lattice showing the uncut end; and,

FIG. 3 is an enlarged fragmentary uncut side view of the plastic molded lattice.

1 Claim, 2 Drawing Sheets

FIG. 1

FIG. 2

FIG. 3
